UNITED STATES PATENT OFFICE.

CHARLES O. LOUKUS, OF MANDAN, MICHIGAN.

DOUBLE-ACTING FOUR-CYCLE EXPLOSION-ENGINE.

1,399,354.

Specification of Letters Patent.

Patented Dec. 6, 1921.

Original application filed January 29, 1920, Serial No. 354,968. Divided and this application filed August 19, 1920. Serial No. 404,538.

To all whom it may concern.

Be it known that I, CHARLES O. LOUKUS, a citizen of the United States, residing at Mandan, in the county of Keweenaw and 5 State of Michigan, have invented a new and useful Double-Acting Four-Cycle Explosion-Engine, of which the following is a specification:

This invention has reference to double acting four-cycle type explosion engines and this application is a division of my application No. 354,968 filed January 29, 1920, for a lubricating and cooling apparatus applied to a similar engine.

15 The object of the invention is to provide a four-cycle type of explosion engine in which the explosions occur twice as often as in an ordinary four-cycle engine, thereby bringing power strokes in such order and 20 rapidity as to greatly steady the working of the engine.

The invention comprises a cylinder and a single piston, the cylinder having inlet and exhaust ports at both ends, spring controlled

25 valves for the ports, rocker arms engaging the valves at one end of the cylinder, other rocker arms engaging the valves at the other end of the cylinder, still other rocker arms connected to the first named rocker arms 30 adjacent to the second named rocker arms, and a single operating means between the second and third named rocker arms for the actuation of all the rocker arms and the valves controlled thereby.

35 The invention will be best understood from a consideration of the following detailed description taken in connection with the accompanying drawings forming part of this specification, with the understanding, 40 however, that the invention is not confined to any strict conformity with the showing in the drawings; but may be changed and modified so long as such changes and modifications mark no material departure from the 45 salient features of the invention as expressed in the appended claims.

Referring to the drawings:

Figure 1 is a vertical section of an engine embodying the invention.

50 Fig. 2 is an elevation on one side of the cylinder end of the engine.

Fig. 3 is an elevation of one side of the upper end of the engine showing some parts in section.

55 Fig. 4 is an elevation of the upper end of

the engine shown in Fig. 1 but viewed from the opposite side thereof.

Referring to the drawings there is shown an engine cylinder 1 provided with heads 2, 3, a reciprocating piston 4, a piston rod 5, 60 posts or supports 6, a crank shaft 7, crank 8 and a fly wheel 9, all of which parts may be, in general, similar in structure to an ordinary reciprocating steam engine but modified in various respects for use with an 65 explosive mixture as the power element.

The cylinder 1 has both heads 2 and 3 connected thereto by bolts 10 and both the cylinder and heads have inter-communicating water jackets 11 for the circulation of 70 cooling water.

The head 2 is provided with inlet and exhaust valves 12, 13, and the head 3 has inlet and exhaust valves 14, 15 respectively. Either of the valves 12 and 13 constitutes 75 an inlet valve and either of the valves 14 and 15 constitutes an inlet valve, while the other valve of each pair constitutes an exhaust valve.

The valves are all of similar construction 80 and each is provided with a valve stem 16 carrying the respective valve head 12, 13, 14 or 15 as the case may be, with a stem passing through an elongated guide 17 continued to the exterior of the cylinder 1 and there 85 furnished with tappet head 18. Each guide 17 is extended beyond the respective ends of the cylinder heads 2 or 3, as the case may be, to there enter one end of a spring 19, the other end of which bears against the tappet 90 18, the arrangement being such that the normal tendency of the spring 19 is to maintain the valve closed.

The tappet end of the stems of the valves 12 and 13 is engaged by rocker arms 20, 95 each carried by a bracket 21 by means of a pivot pin 22.

Similarly the tappet heads 18 on the stems of the valves 14 and 15 are engaged by one end of the rocker arms 23 carried by pivot 100 pins 24 mounted in the posts 6. At each end of each rocker arm 23 are bearing rollers 25, one engaging a respective tappet 18 of the stem of the valve 14 or 15 as the case may be, and the other end is located in the 105 path of a cam 26 carried by a cam shaft 27 provided with bearings and supports 28 which may form part of the post 6. There are two cams 26 carried by the shaft 27 and the latter is provided at one end with a bevel 110

pinion 29 meshing with another bevel pinion 30 on a shaft 31 having a step bearing 32 adjacent to the shaft 7 and there carrying a bevel gear wheel 33 meshing with another bevel gear wheel 34 fast on shaft 27. The shaft 27 also carries other cams 35 engaging respective rollers 36 on the rocker arms 37, each mounted at the end remote from the roller 36 on a pivot pin 38 in one of the posts 6. Each rocker arm 37 is connected by a link 38 with a respective one of the rocker arms 20.

The cycle of operations is that of an ordinary four-cycle explosion engine except that the operations are effective on opposite sides of the piston 4 in such manner that the operations overlap. That is when a charge is entering the cylinder on one side of the piston an explosion may be taking place on the other side of the piston, or the explosion may take place when scavenging is occurring on the other side of the piston. Whatever be the order of operations, the engine is suitably timed to cause the intake, compression, explosion and exhaust on one side of the piston to be so related to the like operations on the other side of the piston that the piston receives two power impulses for each single power impulse of the ordinary four cycle engine. The power of the engine is therefore applied evenly, and correspondingly more power is developed with a less expenditure of energy than is customary. The application of power to the shaft is similar to that of a two-cycle engine with the advantage of a considerable increase in the power impulses. Since the explosion chambers are arranged on both sides of the piston where each acts with the efficiency of a four-cycle engine, the combined efficiency of the engine is materially in advance of a two-cycle engine. The effect is that of two four-cycle engines working in alternation but more economically than occurs with two separate four-cycle engines working side by side or in tandem.

What is claimed is:

1. A double-acting explosion engine provided with a cylinder and a single piston therein, the cylinder having inlet and exhaust ports for both ends thereof, spring controlled valves for the ports, rocker arms engaging the valves at one end of the cylinder, other rocker arms, engaging the valves at the other end of the cylinder, still other rocker arms connected to the first named rocker arms and adjacent to the second named rocker arms, and a single cam shaft located between the second and third named rocker arms to cause the actuation of all the rocker arms for alternately and consecutively controlling the inlet and exhaust valves, the second and third named rocker arms being pivoted independently of each other on the engine. 65

2. A double acting explosion engine provided with a cylinder, a single piston in the cylinder dividing the latter into opposed explosion chambers, inlet and exhaust ports for each chamber, spring-held inlet and exhaust valves for the ports, rocker arms located at one end of the cylinder and adjacent one pair of valves for operating said valves, a second pair of rocker arms mounted at the other end of the cylinder 70 for operating the exhaust and intake valves located thereon, other rocker arms located between the first and second pairs of rocker arms and connected to the first mentioned pair of rocker arms, a cam shaft adjacent 75 one end of the cylinder and located between the second and third pairs of rocker arms and in an offset of the engine, separate pairs of cams on the shaft for operating the second and third pairs of rocker arms, and 80 means for operating the cam shaft, the shaft and pairs of levers being located within the confines of the engine cylinder. 85

In testimony, that I claim the foregoing as my own, I have hereto affixed my signature. 90

CHARLES O. LOUKUS.
